UNITED STATES PATENT OFFICE

FREDERICK PRICE, OF ASHER, OKLAHOMA, ASSIGNOR, BY DIRECT AND MESNE ASSIGNMENTS, TO PRICE-TRAWICK, INC., A CORPORATION OF OKLAHOMA

APPARATUS FOR STARTING THE FLOW OF FLOWING WELLS

Application filed September 15, 1930. Serial No. 482,106.

This invention relates to a method or system for "kicking off" a flowing type oil well, or for "breaking out" such a well to use the terms employed in the larger western and 5 eastern oil fields or, in other words, for starting the flow from the well. It may very appropriately be said to be a flowing well flow starter.

By flowing type well I mean a well in which 10 air or gas under pressure is introduced into the casing to exert a pressure on the top of the column of oil or water or fluid therein to force the said fluid down in said casing and up out of said pipe, or vice versa.

15 This is now a very well known method of extracting oil from wells after the initial or natural gas pressure has become dissipated or dropped to such a low pressure as to fail to force oil or fluid up from the well.

20 Once the natural gas pressure has become so exhausted or reduced as to be inoperative to cause the upward flow of fluid from the well, it is essential to cause such flow by artificial means, either by some mechanical 25 means, as by a rotary pump, or by exerting a pressure on the top of the liquid column in one tubular passage to force a column of the liquid up out of a related tubular passage, such pressure being applied, in practice, 30 by means of air or natural gas under pressure.

This method of extracting the fluid by the application of air or natural gas under pressure has been developed, comparatively 35 speaking, during very recent years, and is by far the preferred method of working or flowing a well because of the fact that the output is not limited by the capacity of any pumping means, the only limit being the flow capacity or size of the tubular passage up through

40 which the fluid flows. Further in more recent wells of great depth, say from 4500 to 8500 feet, it is not practical to pump up the fluid.

45 However, while the method of extracting the oil or fluid from a well by flowing it by air or natural gas pressure is by far the most efficient and preferable, a great difficulty has heretofore been encountered in starting the flow of the fluid up from its natural level 50 through the vertical pipe, casing or conduit

to the surface of the ground. While this difficulty may be overcome without undue expense or inconvenience by old methods in a relatively shallow well, say 2500 to 3000 feet, because the column of oil to be lifted and started in motion or flowing is only 2500 to 3000 feet high and so is of much less weight in total than the corresponding fluid column of say 4500 to 7500 feet in height in a well from 4500 to 7500 feet deep, it has heretofore 55 presented an almost unsurmountable difficulty in deep wells ranging from 4500 to 7500 feet in depth, becoming increasingly more difficult as the depth increases.

In practice under heretofore known methods, it is found that to "kick off", or "break out", or start the flowing of a well it requires about two (2) to two and a half (2½) times the amount of pressure of air or natural gas 60 as it does to keep up the steady normal flow of the same well once it has been started flowing. Just why this is so I am not certain. It may be due to the fact that initially before the air or natural gas introduced as a pressure agent enters the bottom of the tubular conduit, the column of oil to be lifted therein is a solid body of fluid and, further, that it is stationary, whereas after the air or natural gas enters the bottom of said conduit it occupies space that otherwise would be occupied 65 by fluid or oil and also, after the oil once starts flowing, there may be a siphon action or influence that aids in lifting the column. However, whatever the reason for the difference 70 in flow starting and flow maintaining pressures, it is a fact that such differences are found to exist in connection with all flow type wells.

The kicking off or flow starting pressures 75 under the prior practices will vary considerably between several wells of the same depth due to variations between the grades of oil and percentage of water comprising the fluid, but generally speaking the greater the 80 depth of the well the greater will be the pressure required to start the well flowing or kick it off.

85 It is generally accepted now among practical oil men that the closer to the bottom the 90 casing and tubing or bottom intake of oil, 95

55

95

100

the better it is for the well, because you are pulling the oil out of the sand and not pressing the sediments, such as scale and paraffine and other base sediments, back into the sand.

5 With the recent general tendency to drill deeper wells from around 3500 feet to very deep wells of from 7500 feet and over, there has been a very great increase in the pressures required under prior known practices to 10 start the flow, such required pressures often running as high as fifteen to eighteen hundred pounds. When such great pressures as these are employed the compressors become overheated and are apt to jam or "burn up" 15 and there are great risks of the air pipes, or gate valves, or casing heads bursting, resulting in series injuries and even fatalities to the operatives, and even so in the very deep wells it is impractical to kick them off from 20 the bottom of the well, say from a point 5000 feet below the surface of the ground where the oil level is 2000 feet below the ground surface, because it is not practical to build up a sufficient air or natural gas pressure to lift the 25 5000 foot column of oil in the tubular conduit so as to start the flow of fluid from the head of the conduit, prior to the entry of air or natural gas into the bottom of the fluid discharge conduit.

30 In very deep wells by the old method it has been necessary to kick them off at a relatively shallow point in the oil body and thereafter to drop the tubing down in successive stages, involving a new kick off for 35 each stage, which is quite a complicated and very expensive feat and often not successful.

My invention has been developed with the foregoing considerations in view and has for 40 its primary object to provide a method or system for kicking off, breaking out, or starting the flow of a well by an air or natural gas pressure appreciably less than the air or natural gas pressure necessary to maintain such flow of the well after the flow has once been 45 started. After such flow has once been started the same pressure will be required to keep it flowing as is required by previously known methods to maintain the flow, so that my invention is purely and simply a method for 50 kicking off, breaking out, or starting the flow, as distinguished from well flowing apparatus or methods.

My invention also involves, as details, an improved valve construction, a special valved 55 collar unit, yielding means for floatingly maintaining the valve in proper relation for movement with relation to its seat and for permitting the angular movement of said valve with relation to its seat, and various 60 other details.

In the accompanying drawings:

Figure 1 represents a diagrammatic view 65 of an apparatus according to my invention by which my new method invention of "kicking off", "breaking out", or starting the flow of a

flowing type well may be practiced by employing an air compressor or air pump and compressed air tank as the source of compressed gaseous medium;

Figure 2, a view similar to Fig. 1 in which 70 natural gas from a gas well under its natural high gas pressure is used as the source of supply of gaseous pressure medium and connected right on to the pressure lines, the pump or compressor and the pressure storage tank being 75 eliminated;

Figure 3, a vertical sectional view, on a scale approximately two-thirds full size, of 80 one of the valved collars and the adjacent portion of casing and employing the preferred form of double or two-way operating valve in neutral position;

Figure 4, a fragmentary view similar to 85 Fig. 3 with the pressure medium flowing down in the casing as indicated by the arrow, the outer valve having been forced radially inward to closed position by the rush of volume of the pressure medium therethrough;

Figure 5, a view similar to Fig. 4 with the 90 pressure medium flowing down in the tubing as indicated by the arrow, the inner valve having been forced radially outward to closed position by the pressure of the gaseous pressure medium in said tubing;

Figure 6, a cross-section on line 6—6 of 95 Fig. 4;

Figure 7, a detail perspective exploded view of the parts of the valve;

Figure 8, a view similar to Fig. 3 of a modified form of one-way valve, closing 100 radially inward, the gaseous pressure medium being introduced in the casing and passing downward as indicated by the arrow; and

Figure 9, a view similar to Fig. 8 of a further modified form of one-way valve closing 105 radially outwardly, the gaseous pressure medium being introduced in the tubing and passing downward as indicated by the arrow; and

Figure 10, a sectional view, drawn to full size, on line 10—10 of Fig. 6.

Referring now in detail to the drawings. A indicates the air pump or compressor; B the compressed air storage tank; C a pipe line extending between the interior of the top of the casing K and the interior of said tank B to permit the flow of pressure medium, which may be compressed air, from said tank into the top of said casing K; D, pipe connection between compressor A and tank B, E a short pipe connection adapted to establish communication between the interior of the top of the well tubing N and said pipe C, being tapped into, or connected to, the latter by a T connection F; G a main supply valve interposed in said pipe C between the source of pressure medium supply, such as tank B, and the point of communication at F of pipe E with pipe C; H a control valve interposed 120 in the pipe line C between said point F and

125

the top of the casing K; I a control valve interposed in the pipe line E between the point F and the top of the tubing N; J a pressure gage tapped into pipe line E between point F and control valve I; L the casing discharge nozzle at the top of the casing and in communication therewith; O the discharge nozzle at the top of the tubing and in communication therewith; M the casing discharge nozzle control valve, and P the tubing discharge control valve.

With the above arrangement of apparatus, assuming the well to be flowing, if the valves G, H and P are open and the valves I and M are closed the gaseous pressure medium will enter into the casing and work downward therein to maintain the flow of the liquid in the well up through tubing N and out through the tubing discharge nozzle O. If on the other hand the valves G, I and M are open and the valves H and P are closed, the gaseous pressure medium will enter into the tubing and work downward therein to maintain the flow of liquid in the well up through the casing K and out through the casing discharge nozzle L.

The construction, arrangement and operation thus far are known and in general use in the prior known practices of kicking off, breaking out, or starting the flow of, a flowing well, and in thereafter flowing a well and so far as thus described are not new or novel with me, but they have been thus briefly described and fully illustrated because they are employed as elements of the preferred embodiment of my new apparatus employed to practice my new method, system or process of kicking off, breaking out or starting the flow of a flowing well.

My invention considered in its broader aspects involves both a special apparatus for, and a special method or system for, starting the flow whereby air or other gaseous medium under pressure will be admitted successively and cut off at intervals of the vertical conduit containing the liquid to be raised to occupy space therein that would otherwise be occupied by said liquid and so to lighten the total weight of the resultant column of liquid and gas to be lifted or started flowing, whereby the force or pressure required to start the flow in the preferred apparatus is much less than the force or pressure necessary to maintain the flow once it is started, because the gaseous pressure medium occupies a greater percentage of the space in said tubular conduit in the initial starting stage where my apparatus and method are employed than it does during the usual flowing of the well.

In making my apparatus I provide a series of valves 1 respectively controlling ports 2 opening through the side wall of the tubing N and arrange my apparatus with the lower end of the tubing N about thirty feet from the bottom of the well with the lowest port 2 with its cooperating valve 1 disposed pref-

erably one hundred and ten (110) feet from the bottom of the tubing N, the remaining cooperating ports 2 and valves 1 respectively being arranged at the same one hundred and ten (110) foot intervals up to a point one hundred and ten (110) feet below the initial surface of the fluid or surface of the "static head". It is not essential that this exact spacing of one hundred and ten (110) feet be observed, as the apparatus will still function on the same principle to start the flow by the same method, system or process if this spacing interval be varied and the size of the ports 2, valves 1, and, the strength of their springs 3 be modified accordingly. If the spacing interval be modified by decreasing the interval between the respective sets of valves 1 and ports 2 the number of such sets required in a given length of tubing N will be increased while the amount of pressure required to "kick off" or start the flow of, the well will be decreased. For instance if a collar 4 with a port 2 and valve member 1 be interposed between the adjacent ends of each two lengths of pipe, being thus spaced approximately twenty-two feet apart the flow starting or "kicking off" pressure required will be very much less than that required where said collars 4 are interposed in the tubing at the end of each fifth pipe section, that is at intervals of approximately one hundred and ten (110) feet from the bottom of the tubing upward to a point approximately one hundred and ten (110) feet below the level of the "static head" indicated at X. However, the expense of using the collars 4 with their special ports 2 and valve elements 1 between each two pipe sections of the tubing N would be rather excessive and not warranted because spacing at greater intervals is found sufficient to answer the need.

On the other hand spacing at intervals greater than one hundred and ten feet results in rapidly increasing the flow starting or "kicking off" pressure required, it being borne in mind that for each foot of increase of said spacing intervals two additional solid feet of oil or fluid must be vertically raised or lifted two feet in the tubular conduit. In actual practice the method has been efficiently practiced by apparatus such as above described wherein however the collars 4 with their ports 2 and valve members 1 were interposed at intervals of each seven pipe sections, that is, in other words, at intervals of approximately one hundred and fifty four (154) feet, but the flow starting or "kicking off" pressure required was greatly increased, for instance in one well a spacing at 110 feet was used and the flow starting or "kicking off" pressure required was one hundred and fifty (150) lbs. to the square inch, the tubing N was then pulled up, the spacing altered to one hundred and fifty four (154) feet, the tubing N lowered into the casing K of the

well and pressure applied, and the flow starting or kicking off pressure required was one hundred and ninety (190) lbs. to the square inch. In both cases all other conditions were the same, the two tests were conducted within 5 48 hours of each other and the well was flowed through the tubing N in each case. Also, the working or flowing pressure was 10 425 lbs. in each instance, and the volume of gaseous material necessary to flow the well was the same, exactly as under prior known practices.

The essence of my new method or system of flow starting or "kicking off" a well consists simply in successively injecting a 15 quantity of air or gas into the vertical fluid conduit at different preferably equally spaced vertical levels, and closing the port through which each such successive injection is made preferably before the next point 20 of injection is reached until the lowest port 2 is closed by its valve 1 and the gaseous pressure medium works its way down from the last port 2 to the lower end of the tubing and 25 then reverses and comes upward forcing the well fluid up with it, and in maintaining said ports 2, after they have once been closed by their valve members 1, permanently closed thereafter by their said valve members 1 so long as the flow of the well is continued.

In practice I have employed apparatus comprising 2 inch to 3 inch tubing having a 35 port opening of $\frac{1}{2}$ inch closed by a suitable $\frac{5}{8}$ inch valve normally held in neutral position by resilient means yielding radially inwardly under the rush of gaseous pressure 40 rushing through said port from the casing K into the tubing N when the said medium attains a volume of 187 cubic feet per minute 45 to pull the radially outer conical or spherical valve a against the outer valve seat of said port 2 when the gaseous pressure medium is introduced in said casing K. Thereafter 50 a pressure in the casing of thirty-eight (38) pounds serves to hold said radially outer valve a on its seat to keep it closed, whereas a pressure of at least fifty pounds in said casing is necessary to attain a flow of 187 55 cubic feet of gaseous pressure medium through the port 2, so that once closed the valve will remain closed so long as the well is flowing as the flow starting or "kicking off" pressure will always be in excess of fifty 60 (50) pounds and after the flow has once started the pressure will thereafter rapidly build up to its regular working or flowing pressure.

Where the gaseous pressure medium has 65 been introduced through the tubing N the exact same collars 4 with the same size of ports 2 and valve members 1 with radially outer valve a and radially inner valve b have been used and the pressure built up in the tubing 70 N, as distinguished from the rate of flow or

volume of gaseous pressure medium passing through the port 2, is employed to force the radially inner valve radially outward against the resistance of the resilient means to force the said radially inner valve b against the 75 inner seat of said port 2 to close the latter, a pressure of 140 lbs. within said tubing serving to cause this action though of course if the radially outward rush of air through said port 2 attains a volume of 187 cubic feet per minute before such pressure is attained the 80 said inner valve would be closed by volume instead of by pressure.

Thus it will be seen that the preferred form of valve is both a pressure and a volume 85 operated or controlled valve.

The pressure medium may be supplied either by the pump or compressor A with its connected compressed air storage tank B from which the compressed air passes through pipe line C, as illustrated in Fig. 1, or if there is available a source of natural gas under sufficiently high pressure, such as indicated at A', it may be used in substitution for the air compressor A and storage tank B and 90 may be connected by a pipe line B' to the pressure medium supply pipe line C, all as illustrated in Fig. 2.

In the preferred construction of collar 4, a portion of the wall thereof is thickened 95 in a radial direction and preferably vertically slotted with a deep slot extending radially inwardly sufficiently to accommodate, 100 guide, and protect the valve member 1 and its spring 3 and to insure that the valve member 1 will have sufficient room to close in either direction under all conditions. Preferably when the valve b is seated against its corresponding seat of the port 2 the lateral 105 walls of said slot will extend radially outward for about one eighth of an inch beyond the spring 3 and the valve mounting screw f, and of course well beyond the spring 110 mounting screw 6.

Preferably a spacing washer 7 will be disposed about the spring mounting screw 6 between the radially inner face of the spring 3 and the opposed radially inner wall of 115 said slot in order to permit the spring to flex in both directions. Other constructions to this same end may be adapted but this is preferred as most economical of manufacture.

For the same reason the distance from the inner face of the free end of the spring 3, 120 that is the end portion carrying the valve member 1, and the radially inner face of valve a is so calculated that when the radially outer valve a is seated on the outer seat of the port 2 there will be a clearance in a radial 125 direction between the radially inner face of such free end portion of the spring 3 and the adjacent opposed portion of the radially inner wall of said slot, such clearance preferably being about one-eighth of an inch. 130

The preferred construction of valve member 1 consists of a conical or semi-spherical radially inner valve *b* having an axially extending stem *c*, a radially outer centrally axially bored internally screw-threaded valve *a* having a radially outwardly extending spacing shoulder *e* formed with a coned, rounded or convex radially outer end preferably concentric with the axial bore which 5 extends through said valve *a* and shoulder *e*, and a mounting screw *f* which has the radially inner face of its head coned, rounded or convex and presented in opposition to the outer end face of said shoulder *e*, the screw *f* passing 10 through the perforation *g* in the free end of spring 3 and into the screw threaded bore extending through the valve *a* and its shoulder *d*, which are preferably integral with each other as shown. 15

The stem *c* is formed with an outer screw-threaded portion *h* to turn into the valve *a* with a stop shoulder *d* intermediate of the 20 length of said stem and between said screw-threaded portion *h* and the valve *b*, said shoulder *d* being engaged by the radially inner face of valve *a* to maintain the proper 25 distance between the valves *a* and *b*, and the screw-threaded portion is of such length as to extend sufficiently into the bore in the 30 valve *a* to be engaged by the opposed radially inner end of the screw *f* before the latter has been turned in sufficiently to bind the spring 3 between the opposed faces of the shoulder *e* and screw *f*, whereby the valve member 1 35 as a unit will be held positioned by said spring 3 with freedom to wobble to any one of a number of angular positions with respect to the port 2 to seat itself in any one of a number of positions, for instance in case there be any 40 particles of sand or scale on the seats of the port 2, the said valve member 1 may wobble to such an angle that its closing will not be obstructed.

The jamming of the end of screw *f* against 45 the end of portion *h* of course serves to lock both parts in the bore of valve *a*.

Of course, in case the port 2 should become clogged by sand or scale so that the valve *a* or *b* as the case may be could not properly 50 seat itself, the direction of gaseous pressure may be temporarily reversed to blow out the foreign matter and the valves *a* and *b* will serve to limit the movement of the unit 1 and the flexing or bending of the spring 3 to prevent 55 damage to the latter.

The port 2 is preferably a separate disc or cylinder mounted and definitely held in position in the collar 4 by being pressed into an opening in said collar 4 preferably approximately 60 two one-thousandths of an inch less in diameter than said disc or port 2, about two thousand pounds pressure being required to force said ports 2 into position.

Of course any material suitable to the conditions under which the apparatus is to be

used may be employed, but owing to the fact that practically all oil wells have different minerals, salt water, corroding agents, and paraffine and base sediments present in varying degrees, it has been found best to use a 70 non-corrosive metal in the seats, valves, and screws and to protect the spring against corrosion so far as practicable.

I have preferred to employ an alloy known as Monel metal for the ports 2 and all portions of the valve member 1 and to give the 75 spring a soft chromium polish.

In the modification illustrated in Fig. 8 the collar 4 is to be employed in a one-way air or gas pressure medium flowing apparatus, the valve member 1 having only the radially outer valve *a* and the gaseous pressure medium being introduced at the top of the casing *K*, the flow of liquid being limited to flowing through the tubing *N*. Otherwise 80 the construction and operation are the same as in the preferred form.

In the modification illustrated in Fig. 9 the construction and operation are the same as in the modification illustrated in Fig. 8, 85 except that the radially inner valve *b* is retained and the radially outer valve *a* omitted, the gaseous pressure medium being introduced at the top of the tubing *N* and the liquid being limited to flowing through the 90 casing *K*.

I claim:

1. An apparatus for starting the flow of a flowing-type well, said apparatus comprising a casing disposed in a well, a tubing disposed 100 in said casing, and a source of supply of gaseous material under pressure, in combination with a series of valve seats having radially inwardly converging opposed cone faces, a series of double ended valve members respectively extending through said valve seats and each having semi-spherically formed valve heads provided on its end portions and respectively presented in opposition to the respective faces of said seats, said seats and 110 valves being disposed at different vertical levels in the wall of said tubing, yielding means for holding each said valve in neutral position, and means for respectively connecting said valve elements and said yielding 115 means with a universal joint, whereby each said valve may assume any position necessary to seat itself upon its seat under pressure.

2. An apparatus for starting the flow of a flowing-type well, said apparatus comprising 120 a casing disposed in a well, a tubing disposed in said casing, and a source of supply of gaseous material under pressure, in combination with a series of valve seats having radially inwardly converging opposed cone faces, a 125 series of double ended valve members respectively extending through said valve seats and each having semi-spherically formed valve heads provided on its end portions and respectively presented in opposition to the respec- 130

tive faces of said seats, said seats and valves being disposed at different vertical levels in the wall of said tubing, yielding means for holding each said valve in neutral position, and means for respectively connecting said 5 valve elements and said yielding means with a loose joint permitting wobbling movement between them, whereby each said valve may assume any position necessary to seat itself upon its seat under pressure.

10 3. An apparatus for starting the flow of a flowing-type well, said apparatus comprising a casing disposed in a well, a tubing disposed in said casing, and a source of supply of gaseous material under pressure, in combination with a collar interposed in said tubing and having an internal bore of substantially the same diameter as, and in uninterrupted communication with, said tubing in both directions, a valve seat provided in the wall of said collar, a double ended valve member extending through said valve seat and having substantially semi-spherically formed valve heads provided on its end portions and respectively presented in opposition to the respective faces of said seats, and means secured to said collar and yieldingly holding said valve in operative position and permitting the same to wobble with relation to its seat, whereby 15 said valve member may assume any position necessary to seat itself under pressure.

20 4. An apparatus for starting the flow of a flowing-type well, said apparatus comprising a collar adapted to be interposed in the tubing 25 of the well, said collar having an internal bore normally in communication with said tubing in both directions, a valve seat provided in the wall of said collar and having radially inwardly converging opposed concave faces, a valve member extending through said valve seat and having convex valve heads provided on its end portions and respectively presented in opposition to the respective faces of said seat, and means connected to said collar and yieldingly holding said valve member 30 in position and permitting the same to wobble with relation to its seat, whereby said valve member may assume any position necessary to seat itself in either direction upon its seat 35 under pressure.

40 5. An apparatus for starting the flow of a flowing-type well, said apparatus comprising a collar adapted to be interposed in the tubing of the well, said collar having an internal bore of substantially the same diameter as, and adapted to be in uninterrupted communication with, said tubing in both directions, a valve seat provided in the wall of said collar and having a concave face, a valve member extending through said valve seat and having at one end portion a convex valve head opposed to said concave face and provided with an enlargement on its other end portion, and means yieldingly holding said valve member 45 in position and permitting the same to wobble 50 under pressure.

55 with relation to its seat, whereby said valve member may assume any position necessary to seat itself upon its seat under pressure.

In testimony whereof, I have signed my name to this specification at Stroud, Oklahoma, this 13th day of September, 1930.

FREDERICK PRICE.
